(57) **CLAIM**

We claim the ornamental design for a faceplate for a plug-in vaporizer, as shown and described.

DESCRIPTION

FIG. 1 is a front perspective view of a faceplate for a plug-in vaporizer.

FIG. 2 is a front elevation view of the faceplate shown in FIG. 1.

FIG. 3 is a right side elevation view of the plug-in vaporizer shown in FIG. 1. The left side elevation is a mirror image to the right side elevation shown in FIG. 3.

FIG. 4 is a top plan view of the faceplate shown in FIG. 1. FIG. 5 is a bottom plan view of the plug-in vaporizer shown in FIG. 1; and,

FIG. 6 is a rear elevation view of the plug-in vaporizer shown in FIG. 1.

The ornamental design which is claimed is shown in solid lines in the drawings. The broken lines in the drawings are for illustrative purposes only and form no part of the claimed design.
